UNITED STATES PATENT OFFICE.

HERBERT EUGENE FLETCHER, OF LYNN, MASSACHUSETTS.

VALVE-GRINDING MACHINE.

Application filed August 18, 1920. Serial No. 404,463.

To all whom it may concern:

Be it known that I, HERBERT E. FLETCHER, a citizen of the United States, and a resident of Lynn, county of Essex, and State 5 of Massachusetts, have invented certain new and useful Improvements in Valve-Grinding Machines, of which the following is a specification.

The present invention relates more particularly to machines for grinding the faces of valves of internal combustion engines and it primarily aims to provide an electrical motor driven grinding mechanism of a compact arrangement which may be readily set up for use and connected to the ordinary electrical lighting circuit for power and a machine by the use of which valves may be quickly, easily and accurately ground or re-surfaced.

20 The invention has for a further object to provide a valve holding device or chuck for machines of this character which may be easily and readily adjusted so that the face of the valve which is to be ground may at 25 all times be retained in proper position with respect to the grinding element without altering the position or path of travel of the latter.

With the above and other objects in view 30 the invention consists in the novel features of construction, arrangement, combination and formation of parts as will be hereinafter more fully described and particularly pointed out in the appended claims.

35 In the accompanying drawings;

Figure 1 is a plan view of the machine embodying the present invention.

Figure 2 is a side elevation of the same.

Figure 3 is an end elevation, and,

40 Figure 4 is a detailed vertical section through the valve holder or chuck taken on the line A—A of Figure 1.

Referring now more particularly to the drawing wherein like and corresponding parts are designated by similar reference characters throughout the several views. The machine is mounted upon a suitable support comprising preferably of a rectangular base plate 2 having formed therewith 45 and arranged adjacent the medial portion thereof a vertical block 31. This block 31 has formed therewith and extending longitudinally from one end thereof the guide rails or track 32. Arranged upon and adapted to travel upon this track 32 is a carriage 3. Journalled within suitable bear-

ings formed within this block 31 is a screw 23 and the carriage 3 is so connected to this screw that upon the manual rotation thereof through the medium of the hand wheel 8, the carriage will be caused to travel upon the tracks in a longitudinal direction. The upper face of this carriage 3 is provided with a dove-tail track upon which slides a block 4. A screw 24 is also mounted in 60 suitable bearings within the carriage 3 and is so connected to this block 4 that upon the manual rotation of this screw by means of the hand wheel 7, the block 4 will be caused to travel in a lateral direction or in a direction at right angles to the path of travel of the carriage 3. Pivotedly mounted upon this block 4 is a chuck holder which consists of a circular base member 33 having a pair of arms 34 formed therewith and cast with 65 the upper ends of these arms 34 is a sleeve 5 forming a bearing or holder for the chuck. From this construction it is obvious that the chuck holder may be rotated upon the block 4 and retained in its adjusted position by means of the nut 35. The circular base member 33 may be provided with suitable graduation (not shown) so that the adjusted position of the chuck may be readily ascertained.

Secured to and mounted upon this block 31 is an electric motor which may obtain its power from an ordinary lighting circuit. The armature shaft of this motor has secured to one end thereof a grinding element 16 whereas, its opposite end has keyed thereto a pulley 12.

Formed with the chuck holder 5 is a depending arm 36 having a suitable bearing 37 arranged in the lower end thereof. Formed with the base 2 is a vertically extending arm carrying a bearing 38 and journalled within these bearings 37 and 38 is a shaft comprising two sections, 19 and 20 respectively.

These sections 19 and 20 may be connected by means of a slot and pin connection so that they may turn in unison. Freely mounted upon the section 20 of this shaft is a grooved pulley 13 and the latter is connected by means of a belt 30 to the pulley 12 carried by the armature shaft of the motor, so that when the motor 1 is set in motion the pulley 13 will revolve therewith. Slidably mounted upon this section 20 of the shaft is a sleeve 39 and this sleeve 39 is connected through a coil spring 17 to the

shaft. This sleeve 39 carries a cone-shaped clutch member which is adapted to engage with the other member of the clutch carried by the pulley 13 so that when these clutch members are engaged and the pulley 13 rotated, the shaft 20 will be carried therewith. Also formed with the base member 2 is a support 40 having pivotally connected thereto as in 41, a lever 14. One end of this lever 14 is forked and this forked end rests within a groove formed within the sleeve 39 and the opposite end of this lever is provided with a handle (as shown) so that the clutch member 21 may be manually moved 15 into and out of engagement with the clutch member carried by the pulley 13. Arranged within the support 40 is a vertically movable spring pressed pin 15 which extends in the path of travel of the lever 14 and this 20 pin 15 is provided with a handle 42. When the lever 14 is in position, as is better illustrated in Figure 1, the clutch members will be engaged and this pin 15 will retain the lever 14 in this position. When it is desired to disconnect the clutch members, the 25 pin 15 is depressed by pressing upon the handle 42 thereby permitting the lever 14 to be swung upon its pivoted connection.

The section 19 of the shaft is flexible and 30 is enclosed by a flexible casing 18. Keyed to the outer end of this section 19 of the shaft is a pulley 10 over which passes a belt 29 and this belt 29 also passes over the pulley 11.

35 The chuck comprises a head portion 6 having a cylindrical spindle 43 formed therewith and this spindle 43 is journaled within the sleeve 5. One end of the spindle 43 extends beyond the sleeve 5 and has fastened thereto in any suitable or well-known manner the pulley 11 so that the spindle may rotate with the pulley 11. Arranged within the spindle 43 is a tube 44 having the split chuck jaws 26 formed with one end thereof and its opposite end projects beyond the spindle 43 and has connected thereto a hand wheel 9. The outer ends of the chuck jaws 33 are of a conical configuration as is better illustrated in Figure 4, and are 45 adapted to slide within a corresponding recess formed within the head 6 so that upon the longitudinal movement of these jaws they may expand or be brought into gripping engagement with the stems of the 50 valves to be ground. These jaws may be adjusted to the desired position by turning the handle wheel 9. Slidably mounted within the sleeve 44 is a block 27 and arranged between this block 27 and the hand 55 wheel 9 is a coil spring 28.

When grinding the face of a valve, the stem thereof is inserted within the sleeve 44 until the block 27 is forced inwardly 44 until the block 27 is forced inwardly against the tension of the spring 28. By 60 adjusting the hand wheel 9 the jaws 26 will

be brought into gripping engagement with the valve stem thereby holding the valve tightly within the chuck. The chuck may be then advanced or adjusted until the valve is in such a position that it will engage 70 the grinding element 16. The motor 1 is then set in motion and the lever 14 moved so that the clutch members will be brought into engagement whereby the spindle 43 will be set in motion through the mechanism as heretobefore described. As the sleeve 44 carrying the valve stem is held in frictional contact with the spindle 43, by the adjustment of the hand wheel 9 the valve will also be rotated. By turning the hand 75 wheels 7 and 8 the chuck may be so adjusted as to bring the valve into and out of engagement with the grinding wheel 16. When it is desired to remove the valve the clutch members are disengaged by moving 80 the lever 14 thereby stopping the rotation of the valve and by adjusting the hand wheel 9 the chuck jaws will release the valve stem and as the block 27 is exerting the pressure upon the inner end of the valve 85 stem its removal will be greatly facilitated.

Having fully described my invention what I claim as new and desire to secure by Letters Patent is:—

1. A valve grinding machine comprising 95 in combination a support, a carriage adjustably mounted upon said support, a chuck holder adjustably mounted upon said carriage, a motor mounted upon said support, a grinding element carried by said motor, 100 a flexible shaft mounted upon said support, one end of said shaft being operatively connected to said chuck whereby it may rotate therewith, a clutch for operatively connecting said motor with said flexible shaft, and 105 a lever mounted upon said support for operating said clutch.

2. A valve grinding machine comprising 110 in combination a support, a rotatable screw mounted within said support, a carriage adapted to travel in a longitudinal direction upon said support and being operatively connected to said screw, a block slidably mounted upon said carriage, means for causing said block to traverse said carriage 115 a sleeve rotatably supported upon said block, a spindle journaled within said sleeve, chuck jaws carried by said spindle, a hand wheel connected to said chuck jaws for adjusting the same, a motor mounted 120 upon said support, a grinding element carried by said motor, a flexible shaft arranged upon said support, means for operatively connecting one end of said shaft with said spindle, a clutch member for operatively connecting said shaft with said motor and a lever pivotally mounted upon said support for actuating said clutch member substantially as and in the manner set forth.

3. A valve grinding machine comprising 125

in combination, a base plate, a lock on said plate, guide rails extending from one end of said block, a rotatable screw journalled in the block between said guide rails, a carriage mounted on said rails and connected with said screw for longitudinal movement on the rails, a block on said carriage, means to move said block laterally thereof, a chuck holder rotatably mounted on said block, means for adjusting said holder, a chuck in said holder, a motor on the other end of the base plate block, a grinding element carried by the motor, an arm depending from said chuck holder, a bearing in the lower end of said arm, a bearing sleeve on one side of the base plate block, a bearing at the motor end of the base plate, connected shafting disposed in said bearings, driving connection between said motor, shafting and chuck for rotation thereof, and means for regulating said driving connection.

HERBERT EUGENE FLETCHER.
